HATCH CONSTRUCTION

Garth G. Gilpin, Riverside, Ill., assignor to P. H. Murphy Company, New Kensington, Pa., a corporation of Pennsylvania

Application October 28, 1936, Serial No. 107,923

10 Claims. (Cl. 108—5.4)

This invention relates to hatch constructions for metal car roofs, particularly hatch constructions of the kind wherein a metal hatch frame has an uninsulated portion disposed above the general level of the roof and closed by an uninsulated lid and a portion disposed below said level and forming a tapered seat for an insulated hatch plug.

The invention has for its principal object to simplify such a hatch construction by dispensing with the separate tapered heat insulating plug and the special tapered seat provided therefor in the hatch frame. Other objects are simplicity, cheapness and durability of construction. The invention consists in the hatch construction and in the parts and combinations and arrangements of parts hereinafter described and claimed.

In the accompanying drawings, which form part of this specification and wherein like symbols refer to like parts wherever they occur,

Fig. 1 is a plan view of the end portion of a metal car roof provided with a hatch construction embodying my invention;

Fig. 2 is a vertical partial cross-section thereof on the line 2—2 in Fig. 1;

Fig. 3 is a partial longitudinal section on the line 3—3 in Fig. 1;

Fig. 4 is an enlarged fragmentary section similar to Fig. 2 through one side of the hatch construction;

Fig. 5 is an enlarged fragmentary section similar to Fig. 3 through one side of the hatch construction; and

Figs. 6, 7, 8 and 9 are views similar to Fig. 5 illustrating four modified forms of hatch construction.

The metal car roof illustrated in the accompanying drawings comprises end and intermediate roof sheets 1 and 2, respectively, that extend from side plate 3 to side plate 3 of the car with their eaves ends secured to eaves angles 4 fixed to the side plates. The end and intermediate roof sheets are provided along their adjacent margins with upstanding flanges 5 that are covered and secured together by a seam cap 6. At the end of the car, the end sheet 1 is secured to an end angle fixed to a metal end plate 7.

The roof is provided with one or more hatchways that lead downwardly into the interior of the car through the end roof sheet 1 and a framework located therebelow. Said framework preferably comprises spaced parallel frame or carline members 8, which extend from side plate to side plate with their ends secured thereto by brackets 9, and spaced parallel cross frame members 10

that are secured to and flush with the tops of said carline members and cooperate therewith to define the hatchway opening in said framework. As shown in the drawings, the carline members 8 and cross members 10 of the framework comprise metal angles disposed with one flange up and extending outwardly at a slight upward inclination, said flanges forming a continuous supporting surface around the opening in said framework.

Each of the hatchways is provided with a metal hatch frame. The metal hatch frame shown in Figs. 1 to 5 of the drawings comprises a relatively wide upper portion 11 located above the general level of the roof, a relatively narrow lower portion 12 located between and resting flatwise against the inner faces of the carline and cross-frame members, and a shoulder 13 that rests upon the sloping top flanges of said members. The wide upper portion 11 of the metal hatch frame has upwardly converging side walls that terminate at the top of said frame in an inwardly extending flange 14 that constitutes a seat for a lid or cover 15 that is provided with a filler 16 of suitable heat insulating material; and the narrow lower portion 12 of said frame is of uniform width from top to bottom. The hatch frame is rigidly secured to the carlines and cross frame members preferably by welds 17 that extend along the longitudinal edges of said members. The end or hatch sheet 1 is provided around the hatch opening therein with an upstanding flange 18 that is secured to the wide upper portion 11 of the hatch frame by a weld 18a that extends continuously along the top edge of said flange.

The inwardly extending cover supporting flange 14 at the top of the hatch frame is a relatively wide flange that cooperates with the converging side walls and the connecting web or shoulder of said frame to form an inwardly opening channel 19 in the relatively wide upper or rim portion thereof. Mounted in this inwardly opening channel is a heat insulating frame 20 of wood or other rigid heat material that is secured in said channel preferably by means of bolts 21. This frame or filler 20, together with the insulated cover 15, serves to insulate the upper portion of the hatch frame, thereby dispensing with the insulated plug and the tapered seat required therefor in said hatch frame. The rigid insulating frame also tends to stiffen and strengthen the exposed upper portion of the frame. The insulated frame may be attached to and removed from the roof as a complete preassembled unit; and

the insulating filler may be readily removed and replaced without disturbing the frame.

In the modification shown in Fig. 6, the inwardly opening channel in the large upper portion of the metal hatch frame is provided with a filler 20a of loose, fibrous heat insulating material which is retained in said channel by means of a closure plate 22 that is secured along its upper and lower edges to the frame by welds 23.

10 The modification shown in Fig. 7 is similar to that shown in Fig. 6, except that the top flange of the channel is bent downwardly, as at 24 at its free end to retain the upper margin of the cover plate 22a in place, thereby dispensing with 15 the uppermost securing weld shown in Fig. 6.

In the modification shown in Fig. 8, the lower narrow portion of the hatch frame is made in the form of a separate member 12a that is welded to the wide upper portion 11a of said frame and is 20 extended upwardly across the insulation receiving channel thereof to form a closure therefor.

25 In the modification shown in Fig. 9, the upwardly extended portion of the narrow member 12b of the hatch frame has an outstanding flange 12c, which forms the top wall of the channel in the enlarged upper portion of said frame, and an angle-shaped member 11b has one flange welded to said top flange and its other flange welded to 30 said narrow member to form the side and bottom walls of said channel.

What I claim is:

35 1. A hatch construction for a car roof comprising a metal hatch frame having a portion extending above the general level of the roof and provided with an inwardly opening channel, and heat insulating material mounted in said channel.

40 2. A hatch construction for a car roof comprising a metal hatch frame having a portion extending above the general level of the roof and provided with an inwardly opening channel, and a filler of rigid heat insulating material in said channel.

45 3. A hatch construction for a car roof comprising a metal hatch frame having a laterally offset portion extending above the general level of the roof and provided with an inwardly opening channel, and a filler member in said channel.

50 4. A hatch construction for a car roof comprising a metal hatch frame having a laterally offset portion extending above the general level of the

roof and provided with an inwardly opening channel, and a wooden filler in said channel.

5 5. A hatch construction for a car roof comprising a metal hatch frame having a portion extending above the general level of the roof and provided with an inwardly opening channel, loose heat insulating material in said channel, and a closure member for said channel.

10 6. A hatch construction for a car roof comprising a metal hatch frame having a portion extending above the general level of the roof and provided with an inwardly opening channel, loose heat insulating material in said channel, and a metal plate welded to said metal hatch frame and closing said channel.

15 7. A hatch construction for a car roof comprising a metal frame made up of a section having a portion extending above the general level of the roof and a section surrounding said portion and cooperating therewith to form a closed hollow rim portion, and a filler member in said hollow rim portion.

20 8. A hatch construction for a car roof comprising a metal frame made up of a section having a portion extending above the general level of the roof and a section surrounding said portion and cooperating therewith to form a closed hollow rim portion, and heat insulating material in said hollow rim portion.

25 9. A hatch construction for a car roof comprising a metal frame made up of a section having a portion extending above the general level of the roof and a section of channel shaped cross section cooperating with said portion of said first mentioned section to form a closed hollow rim portion, and a filler of heat insulating material in said hollow rim portion.

30 10. A hatch construction for a car roof comprising a metal frame made up of a section having a portion extending above the general level of the roof and a second section cooperating with said portion of said first mentioned section to form a closed hollow rim portion, and heat insulating material in said hollow rim portion, said first mentioned section terminating at its upper 40 end in an outstanding flange that forms the top of said hollow rim portion and said second section comprising a frame of angle-shaped cross-section arranged with one flange forming the outer side wall of said hollow rim portion and with the other flange forming the bottom wall thereof.

45 GARTH G. GILPIN.
